NECKTIE CONSTRUCTION

Rudolph Naftali and Esther Naftali, New Rochelle, N. Y.

Application April 27, 1953, Serial No. 351,293

3 Claims. (Cl. 2—151)

This invention relates generally to the field of neckwear, and more particularly to an improved form of simulated bow tie.

One of the principal objects of the invention is to provide necktie means so constructed and arranged that a novel type of bow-knot may be quickly formed without the requirement of any special knowledge or skill on the part of the wearer which is usually required in forming the bow-knot of conventional bow ties.

Another object of the invention lies in the provision of simulated bow tie structure of the class described in which the tying operation is performed at the simulated knot, rather than in the rear as has been the case in prior art constructions. This materially lessens the difficulty involved in donning and doffing the structure.

Another object of the present invention lies in the provision of simulated bow tie structure providing the above enumerated advantages, in which the cost of fabrication may be of a relatively low order, with consequent wide sale, distribution and use.

A feature of the invention lies in the fact that, not only is the device more readily tied than is the case with conventional bow tie constructions, but a substantial saving in the amount of material employed is also realized by the novel structure.

Another feature of the invention lies in the fact that no elastic structure is necessary in any portions of the device, thereby assuring that the wearing of the same will be appreciably more comfortable than has heretofore been the case.

Still another feature of the invention lies in the provision of simulated bow tie structure which lacks the "pre-tied" appearance which many users have heretofore found objectional.

These objections and features, as well as other incidental ends and advantages, will become more clearly apparent during the course of the following disclosure, and be pointed out in the appended claims.

On the drawing, to which reference will be made in the specification, similar reference characters have been employed to designate corresponding parts throughout the several views.

Figure 1 is a view in perspective showing an embodiment of the invention in position upon the neck of a wearer.

Figure 2 is a view in elevation showing the embodiment in a planar condition.

Figure 3 is a second view in elevation showing the reverse side of the embodiment when the same is in a planar condition.

Figure 4 is a fragmentary enlarged horizontal longitudinal sectional view corresponding to that seen from the plane 4—4 on Figure 2, with certain structure removed for purposes of clarity.

Figure 5 is a fragmentary enlarged horizontal longitudinal sectional view as seen from the plane 5—5 on Figure 1.

2

Figure 6 is a fragmentary view in elevation showing an alternate form of the embodiment.

Figure 7 is a fragmentary enlarged vertical transverse sectional view as seen from the plane 7—7 on Figure 6.

Figure 8 is a sectional view corresponding to that seen on Figure 7, but showing a second alternate form of the embodiment.

In accordance with the invention, the device, generally indicated by reference character 10, comprises broadly:

10 a main body element 12, a first tie tab element 14, a second tie tab element 16, and a knot-retaining ring element 18.

The main body element 12 is fabricated using necktie manufacturing techniques well known in the art. The element may be of a two ply type including an inner face or lamina 20, and an outer face or lamina 22. As may be seen on Figures 2 and 3, the main body element 12 is of elongated configuration and includes a first end 21 and a second end 23. If desired, conventional adjusting means 24 may be provided at the central portion of the main body element so that the device 10 may be adjusted to a wide variety of neck sizes. The element 12 is of generally orthodox configuration, including an upper edge 26, a lower edge 28, converging edges 30 and 32, which meet at a point designated by reference character 34, and converging edges 36 and 38 which meet at a point indicated by reference character 40.

The first and second tie tab elements 14 and 16 are generally similar, and accordingly, to avoid needless repetition, a detailed description of the first tie tab element 14 will serve equally well to describe the second tie tab element 16.

The element 14 is formed by folding a single layer of cloth to form an inner layer 41 and an outer layer 43 (see Figure 4). The folded element 14 is of generally trapezoidal shape, including an upper edge 42, a lower edge 44, an inner edge 46, and an outer edge 48. Stitch means 50 is employed to secure the points adjacent to the inner edge 46 to the main body element 12, the stitching covering an area indicated by reference character 52. The stitches are preferably of a color identical with the color of the cloth from which the entire device 10 is made, although, as may be seen on Figure 5, when the device is completely tied, the stitched areas are concealed beneath the element 18.

As has been mentioned, the element 16 is generally similar to the element 14, including inner and outer layers 54 and 56, which are bounded by upper and lower edges 58 and 60, and inner and outer edges 62 and 64. Similar stitch means 66 extends over the stitched area 68.

Immediately adjacent the stitched area 68, and extending parallel thereto, is an elongated slot 70 which extends through the main body element 12. The slot 70 is of a length substantially equal to the width of the element 12 at that point, a margin approximately $\frac{1}{16}$ of an inch between the ends of the slot and the upper and lower edges 24 and 26 being retained for purposes of strength. To avoid the possibility of the slot becoming frayed, button hole stitching 72 is used to bind the edges.

60 The ring element 18 is formed with an inner lamina 74 and an outer lamina 76. The side edges 78 and 80 are generally convex, as may be seen on Figure 4, to insure that the stitched areas 52 and 68 are completely covered when the device is tied. As may be seen on Figure 3, the concealed portion of the element 18 is inserted between the lamina 20 and 22, and stitched therebetween at the time of integration of the lamina 20 and 22.

The device is tied by slipping the central part of the main body element beneath the collar as is the case in conventional ties, after which the ends 21 and 23 are brought forwardly beneath the chin of the wearer. At this point, the end 21, together with the first tie tab ele-

ment 14 are passed into the slot 70, and the end 23, together with the second tie tab element 16 are passed beneath the ring element 18, so that the parts assume the position shown on Figure 5. Where the adjusting means 24 has been placed at the proper setting, the tie will assume the external appearance shown on Figure 1, where the effect of a conventional bow tie is achieved. The tie may be removed by slipping the fingers of the hands of the wearer beneath the collar points and grasping the portions of the main body element 12 disposed therebeneath. A gentle outward pull will serve to separate the ends from engagement with each other, after which the tie may be removed from the neck of the wearer.

In the alternate form of the embodiment shown on Figure 1, the ring element 18 is made in the form of an elongated strap permanently fastened at one end thereof to the lamina 22, and the other end of which is fastenable thereto in juxtaposed relationship. This structure is accomplished by means of a snap fastener 94, including a male portion 96, and a female portion 98. The element is generally of the same configuration as is the case in the principal form of the embodiment, including convex side edges 86 and 88 and end edges 90 and 92.

In the second alternate form of the invention shown on Figure 8, the element 18 is in the form of an endless ring which is slidably disposed upon the main body element 12. When employing this form of the invention, the element 18 is slid to one side, until the end 21 is engaged with the slot 70, after which the same is slid over the end 21 to the position shown on Figure 1, wherein the external appearance of the device will be the same as the other forms of the embodiment.

It may thus be seen that there has been invented novel and highly useful improvements in necktie constructions, in which all of the major difficulties involved in tying a bow tie have been substantially eliminated. The device may be properly positioned with less effort than is normally employed in the making of a four-in-hand type of necktie, and may be removed with still less effort on the part of the wearer. The device is simple in construction, and may be fabricated at a cost no higher than involved in the manufacture of conventional bow ties, and with a substantial saving in material.

It is to be understood that it is not considered that the invention is limited to the exact details of structure shown and set forth in the specification, for obvious modifications will occur to those skilled in the art to which the present invention pertains.

What is claimed is:

1. A device for use by a wearer for forming a simulated bow tie comprising: an elongated main body element adapted to encircle the neck of said wearer; first and second tie tab elements; said main body element having first and second end portions; said tie tab elements each comprising a shaped and folded cloth lamina stitched along free edges thereof to one of said end portions; said main body portion having a principal longitudinal axis and an elongated slot extending therethrough, the axis of which lies substantially perpendicular to said principal axis; said slot being positioned adjacent one of said end

5

portions; said device in formed condition having the end portion and attached tie tab more distant from said slot inserted through said slot; and a knot forming ring encircling said main body element, and positioned to substantially cover said slot, whereby the points of interconnection of said tie tabs and said end portions may be concealed beneath said knot forming ring.

10

2. A device for use by a wearer for forming a simulated bow tie comprising: an elongated main body element adapted to encircle the neck of said wearer; first and second tie tab elements; said main body element having first and second end portions; said tie tab elements each comprising a shaped and folded cloth lamina stitched along free edges thereof to one of said end portions; said main body portion having a principal longitudinal axis and an elongated slot extending therethrough, the axis of which lies substantially perpendicular to said principal axis; said slot being positioned adjacent one of said end portions; said device in formed condition having the end portion and attached tie tab more distant from said slot inserted through said slot; and a knot forming ring encircling said main body element, and positioned to substantially cover said slot, whereby the points of interconnection of said tie tabs and said end portions may be concealed beneath said knot forming ring; said ring forming an integral part of said main body element.

20

3. A device for use by a wearer for forming a simulated bow tie comprising: an elongated main body element adapted to encircle the neck of said wearer; first and second tie tab elements; said main body element having first and second end portions; said tie tab elements each comprising a shaped and folded cloth lamina stitched along free edges thereof to one of said end portions; said main body portion having a principal longitudinal axis and an elongated slot extending therethrough, the axis of which lies substantially perpendicular to said principal axis; said slot being positioned adjacent one of said end portions; said device in formed condition having the end portion and attached tie tab more distant from said slot inserted through said slot; and a knot forming ring encircling said main body element, and positioned to substantially cover said slot, whereby the points of interconnection of said tie tabs and said end portions may be concealed beneath said knot forming ring; said ring being in the form of an elongated strap permanently fastened at one end thereof to said main body portion and having a free end provided with snap fastener means interconnectable with said main body portion.
